UNITED STATES PATENT OFFICE.

FREDERICK M. RAUCH, OF WASHINGTON, DISTRICT OF COLUMBIA, ASSIGNOR OF ONE-HALF TO WALTER J. BROOKS, OF WASHINGTON, DISTRICT OF COLUMBIA.

GARMENT HANGER.

Application filed November 10, 1923. Serial No. 674,014.

To all whom it may concern:

Be it known that I, FREDERICK M. RAUCH, a citizen of the United States, residing at Washington, in the District of Columbia, have invented certain new and useful Improvements in Garment Hangers, of which the following is a specification, reference being had to the accompanying drawings.

This invention relates to garment hangers, and particularly to that class of garment hanger wherein there is provided a garment detainer having upwardly extending garment-engaging shoulders disposed on each side of the middle thereof and adapted 15 to engage the neck of a garment.

In dry goods stores where garments are put up for sale on hangers and where they are constantly being handled, it is difficult to keep the garment from slipping off the hanger, particularly where the garment has a relatively wide neck. The garments are liable to slip off the hanger and onto the floor and remain there until the clerks pick them up and replace them on the hangers. 20 In order to prevent this, it is necessary to provide the garment hanger with upwardly extending shoulders disposed on each side of the middle of the hanger and adapted to engage the neck of the garment to hold the 25 neck expanded and prevent the hanger from accidentally shifting within the garment.

The general object of the present invention is to provide a garment retainer for hangers of this character which may be 30 cheaply made of resilient wire and which are adapted to be engaged with the arms of the hanger and slide thereon, and which are further so constructed that though the retainers may be readily shifted outward on 35 the arms of the hanger, they cannot be readily or accidentally shifted inward.

A further object is to provide a device of this character which is provided with an upwardly and outwardly extending finger 40 which will engage with and overhang the opening of the garment so as to prevent the accidental detachment of the garment from the hanger, these retainers being adapted to be shifted along the arms of the garment 45 until the garment is fully engaged with the hanger and cannot accidentally become detached.

A still further object is to provide a device of this character which is very simple, 50 which may be cheaply constructed, and

which may be made so as to fit all standard sizes of hangers.

My invention is illustrated in the accompanying drawings, wherein:—

Figure 1 is a side elevation of a garment hanger provided with my improved retainers;

Figure 2 is a section on the line 2—2 of Figure 1;

Figure 3 is an under side fragmentary plan view of one arm of the hanger showing the retainer applied thereto;

Figure 4 is a perspective view of one of the retaining cleats.

Referring to these drawings, 10 designates an ordinary form of garment hanger made of an arcuate strip of wood, composition or like material, this strip being relatively thin and having rounded upper edges. The strip at its middle is engaged by a supporting hook 11.

Disposed upon the arms of the hanger 10 are the retainers, designated generally 12, which are preferably made of a single piece of resilient wire bent as will be hereafter stated, this wire being bent to form a hanger embracing loop 13, an upwardly and rearwardly directed finger 14, and a spring 15 terminating in a slight coil constituting a head 16. The retainer is placed upon the arm of the garment hanger, as shown in Figure 1, with the finger 14 directed upward and outward and with the loop 13 disposed at an angle less than a right angle to the longitudinal axis of the arm. The spring 15 bears against the lower edge of the hanger, and it is the resiliency of this spring which urges the hanger into the inclined position illustrated in Figure 1.

By pressing upon the finger 14 toward the end of the hanger, it is possible to force the hanger outward along the arm, this acting to shift the loop 13 into a position at right angles to the axis of the arm. The finger 14 is formed by a loop, the ends of which are crossed at the intersection of the finger 14 with the loop 13, and the resilience of the wire causes this loop 12 to resiliently contract upon the arm of the hanger. When an effort is made to shift the detainer toward the middle of the hanger, however, any pressure against the upper end of the detainer tends to cramp the loop on the arm and cause it to bind so that it cannot accidentally be moved toward the hook.

While I do not wish to be limited to any particular means for forming this detainer, I preferably construct it, as before stated, of one piece of wire. This piece is bent to 5 form the hook 17, then bent to form one half of the loop 13, then laterally bent and bent to form one-half of the finger 14, then returned upon itself to form the other half of the finger 14 and the other half of the 10 loop 13, and then engaged with the hook and bent longitudinally to form the spring finger 15 and the scroll 16 at the end thereof. It is obvious that this detainer clip might be constructed in other ways than 15 this, but I have found this particularly convenient and effective and at the same time very cheap.

A device of this kind may be readily applied to all forms of garment hangers which 20 are rectangular in cross section, but it is obvious that the detainer may be adapted to fit hangers which are otherwise formed in cross section. It is to be noted that the fingers 14 overhang the margins of the neck of 25 the garment so that the garment is not only held from shifting movement upon the hanger but is held from accidental upward movement. Thus the garments are kept in good shape, retained upon the hangers without danger of being accidentally disengaged 30 therefrom, and the hanger and the garment may be handled without chance of the garment dropping off the hanger.

It is to be understood that while the retainer is movable readily by design toward 35 the end of the arm, yet it will not accidentally move but clasps the arm of the garment hanger sufficiently closely so that it will stay wherever it may be placed until designedly 40 shifted.

I claim:—

1. A garment retainer for garment hangers comprising a loop adapted to slidably engage the arm of a garment hanger 45 and having an upwardly and outwardly extending garment retaining finger, the lower end of the loop being formed with an up-

wardly and inwardly extending spring adapted to bear against the under side of said arm and to yieldingly hold the loop 50 clamped upon the arm.

2. A garment retainer for garment hangers formed to provide an arm embracing loop, a finger extending upward and outward from the upper end of the loop, and a spring extending from the lower end of the hanger engaging loop and extending upward and inward and adapted to engage with the under face of the hanger arm and urge the loop into tilted position with relation to the arm and cause the loop to bind upon the arm against movement in one direction but permitting the loop to have free movement upon the arm in the other direction.

3. A garment detainer for garment hangers of the character described formed of resilient wire and comprising a loop adapted to embrace the arm of the garment hanger, the loop being formed in oppositely disposed independent portions, the wires at the upper end of the loop crossing each other and being formed to provide an elongated looped finger extending upward and outward, one of the wires at the lower end 75 of the loop being engaged with the other wire and then longitudinally and upwardly extended to form a resilient finger engaging the lower edge of the garment hanger.

4. A garment hanger having a supporting member, arms extending in opposite directions from the supporting member and a garment retainer disposed on each arm, the retainer when disposed at right angles to the length of the arm being slideable longitudinally of the arm and when canted at less than a right angle to the arm having clamping engagement with the arm, each garment retainer having a garment retaining finger at its upper end.

In testimony whereof I hereunto affix my signature.

FREDERICK M. RAUCH.
